(57) CLAIM

The ornamental design for a toy ferris wheel, as shown and described.

DESCRIPTION

FIG. 1 is a front perspective view of a toy ferris wheel showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The features shown in broken lines are portions of the toy ferris wheel forming no part of the claimed design. The features shown in long dash-short dash bolded broken lines indicate the bounds of the claimed design and otherwise form no part of the claimed design.

1 Claim, 6 Drawing Sheets
